UNITED STATES PATENT OFFICE.

ERMINIO TOMMASI, OF MILAN, ITALY, ASSIGNOR TO THE SINGER MANUFACTURING COMPANY, OF ELIZABETH, NEW JERSEY, A CORPORATION OF NEW JERSEY.

NEEDLE MECHANISM FOR SEWING MACHINES.

Application filed April 12, 1926. Serial No. 101,859.

This invention relates to sewing machines, more particularly of the type having upper and lower eyed thread-carrying implements which cooperate with one another to form 5 stitches. Machines of this type commonly embody a stop-motion device which automatically arrests the main-shaft in a pre-determined angular position with the sewing instrumentalities clear of the work. Lower 10 thread-carrying implements are generally difficult to thread due to their positions of relative inaccessibility and an object of the present improvement is to provide for easy threading of the under thread-carrying implement without the necessity of tripping the 15 stop-motion device and turning the main sewing shaft, after which the machine must be run idly through a complete cycle of operations to starting position before it is 20 ready to sew.

To the attainment of the ends in view there is provided in the train of mechanism between the main sewing shaft and the under thread-carrying implement, a manually operable disconnecting means whereby 25 such implement may be temporarily disconnected from its driving shaft and projected above the work-support for easy threading. The disconnecting means preferably 30 comprises a spring-pressed pin-member and a socket-member with independent carriers therefor connected, respectively, to the main-shaft and under thread-carrying implement.

In the accompanying drawings Fig. 1 is 35 a side elevation, partly in section, of a buttonhole sewing machine embodying the invention. Fig. 2 is a front end elevation, partly in section, of the under needle actuating mechanism, and Fig. 3 is a section on 40 the line 3-3, Fig. 2.

The invention is shown as embodied in a sewing machine of the buttonhole type having a frame formed with a hollow rectangular bed *a* from which rises the standard *b* 45 of the overhanging bracket-arm *c* terminating in the head *d*.

The stitch-forming mechanism may be of any suitable type. In the present machine it is constructed substantially in accordance 50 with the disclosure of the patent to E. B. Allen, No. 1,162,207, of November 30, 1915, and embodies the upper reciprocating straight eye-pointed needle 1 and the lower curved eye-pointed needle 2 which is sustained by the rotary turret 3. The needle

1 is carried by the needle-bar 4 and the usual turning movements, as for stitching the ends of a buttonhole, are imparted to the needle-bar and turret by means of the upper and lower sector-gears 5, 5', connected by links 6, 7, to arms 8, 9, on the shaft 10; the arm 9 having a cam-follower 11 entering the usual stitch-rotating cam-groove 12 in the feed-wheel 13, as disclosed in said patent.

The buttonhole cutting mechanism including the travelling cutter-levers 14, 15, the work-holder mechanism including the lower plates 16 and upper clamping feet 17, and the several remaining elements of the machine not herein specifically set forth are 65 preferably constructed substantially in accordance with the disclosure of the patent to E. B. Allen, No. 1,346,102, of July 13, 1920.

The under needle 2 is mounted on the 75 needle-carrier arm 18 which is fulcrumed at 19 on the supporting post 20 rising from the turret 3. The needle-carrier arm 18 is connected by the link 21 to the vertically moving head 22 fixed to the upper end of 80 the sleeve-shaft 23 slidably mounted within the hollow turret spindle 24. Slidably mounted in bearings 25, 25, in parallelism with the shaft 23 is a shaft 26 to which is fixed a lateral arm 27 having a forked extremity 28 embracing the groove 29 in the shaft 23 and thus connecting the shafts 23 and 26 to reciprocate in unison. It will be understood that reciprocation of such shafts 85 imparts the usual reciprocating movements 90 to the under needle 2, carrying the latter from a position below the needle-throat member or work-support 30 to a position above the same, and return. The needle 2 carries a loop of under thread through the 95 work and presents such loop at the upper side of the work for entry by the upper needle 1 which passes a loop of upper thread through the loop of under thread and through the work. A suitable looper device 100 31, such as disclosed in said Patent No. 1,162,207, seizes a loop of upper thread from the upper needle and presents such loop for entry by the under needle on its upward passage through the work.

The shaft 26 is connected by means of the link 32 to the lever-arm 33 which is fulcrumed, together with a shorter arm 34 on the pin 35 fixed to the frame. The arm 34 is formed at its upper end with a bearing 105 110

pin 36 having a socket 37 and embraced by one end of a link 38 the other end of which embraces a crank 39 on a shaft 40 which is geared at 41 to the main sewing shaft 42, the period of action of which is controlled by the usual stop-motion device 43 (disclosed for example in said Patents Nos. 1,162,207 and 1,346,102), which stops and locks the shaft 42 in a predetermined angular position 10 with the needles 1 and 2 out of the work. The arms 33 and 34 are coupled together for transmission of operative sewing movements to the needle 2 by means of the spring-pressed coupling pin 44 carried by the lever 33 and entering the socket 37 in the arm 34.

When the machine is at rest the lower needle is normally below the work-support 30 and the parts of its driving mechanism are in full line position, Fig. 2. With the parts 20 in this position the operator may grasp the knob 44' of the pin 44 and withdraw the latter from the socket 37 whereupon the lever 33 may be manually shifted to dotted line position, Fig. 2, to project the needle 25 2 to easy threading position above the work-support. After the needle 2 has been threaded, the operator should shift the lever back to initial position wherein the pin 44 registers with the socket 37 and enters the latter 30 when released by the operator.

Having thus set forth the nature of the invention, what I claim herein is:—

1. In a sewing machine, in combination, a work-support, an under thread-carrying implement disposed below the work-support, a main-shaft, operative connections between said shaft and thread-carrying implement, a stop-motion device for stopping said main-shaft with the thread-carrying implement 35 below the work-support, and means for projecting said thread-carrying implement above the work-support without disturbing said stop-motion device.

2. In a sewing machine, in combination, a work-support, an under thread-carrying implement disposed below the work-support, a main-shaft, operative connections between said shaft and thread-carrying implement, a stop-motion device for stopping said main-shaft with said thread-carrying implement below the work-support, said connections including coacting pin-and-socket members, independently movable carriers for said members connected, respectively, to the 50 main-shaft and under thread-carrying implement, one of said members being manually withdrawable from working engagement with the other member to permit the under thread-carrying implement to be projected above the work-support for easy threading without disturbing said stop-motion device.

3. In a sewing machine, the combination with a work-support and stitch-forming mechanism including an eye-pointed under thread-carrying implement disposed below the work-support, of a driving shaft, operative connections between said driving shaft and said under thread-carrying implement, and a stop-motion device for arresting said shaft with the under thread-carrying implement below the work-support, said operative connections including a manually operable disconnecting means permitting the under thread-carrying implement to be projected above the work-support without disturbing the stop-motion device. 65

4. A sewing machine of the buttonhole type having, in combination, stitch-forming devices including upper- and under-needle mechanisms, a rotary turret on which the under-needle mechanism is mounted to partake of its working movements, a needle-throat member, a work-holder, a main sewing shaft, driving connections between said main shaft and said under-needle mechanism, means for relatively moving the stitch-forming devices and work-holder to sew a group of stitches, and a stop-motion device for arresting said shaft at the completion of a sewing period with the needles 80 out of the work, said driving connections including a manually operated element for uncoupling said under-needle mechanism from said main-shaft and projecting the under-needle above the needle-throat member. 85

5. A sewing machine of the buttonhole type having, in combination, stitch-forming devices including upper and under needle mechanisms, a rotary turret on which the under needle-mechanism is mounted to partake of its working movements, a needle-throat member, a work-holder, a main sewing shaft, driving connections between said main-shaft and said under needle mechanism, means for relatively moving the stitch-forming devices and work-holder to sew a group of stitches, and a stop-motion device for arresting said shaft at the completion of a sewing period with the needles out of the work, said driving connections including coacting pin-and-socket members between said main-shaft and said turret, one of said members being spring-pressed and manually withdrawable from working engagement with the other member to disconnect said under needle mechanism from said main-shaft and permit said mechanism to be manually operated to project the under needle 100 above the needle-throat member. 105

In testimony whereof, I have signed my name to this specification.

ERMINIO TOMMASI.
